MATCH HOLDER, EJECTOR, AND LIGHTER

Filed March 25, 1924

FIG. 3.

FIG. 4.

INVENTOR
JULIUS CASACCIA
BY
Lindley Johnson
ATTORNEY

Patented Sept. 21, 1926.

1,600,622

UNITED STATES PATENT OFFICE.

JULIUS CASACCIA, OF SAN FRANCISCO, CALIFORNIA.

MATCH HOLDER, EJECTOR, AND LIGHTER.

Application filed March 25, 1924. Serial No. 701,713.

This invention relates particularly to a case in which matches may be held, and automatically ejected and lighted.

An object of the invention is to provide a match carrying magazine from which matches may be withdrawn individually by a manually operable mechanism and automatically ignited during movement of withdrawal.

10 A further object of the invention is to provide a match carrying magazine in which the matches will be automatically advanced to the point of ejection.

15 Other objects of the invention are to provide a match carrying magazine of the character described that will be superior in point of simplicity, inexpensiveness of construction, positiveness of operation, and facility and convenience in use and general 20 efficiency.

In this specification and the annexed drawings, the invention is illustrated in the form considered to be the best, but it is to be understood that the invention is not limited 25 to such form, because it may be embodied in other forms, and it is also to be understood that in and by the claims following the description, it is desired to cover the invention in whatsoever form it may be embodied.

30 In the accompanying one sheet of drawings:

Fig. 1 represents a plan view of a match holder, ejector and lighter, constructed in accordance with my invention.

35 Fig. 2 is a cross-section taken through Fig. 1, on the line 2—2.

Fig. 3 is an enlarged end view of Fig. 1.

Fig. 4 is a cross-section taken through Fig. 4, on the line 4—4.

40 In detail the construction illustrated in the drawings comprises an elongated, rectangular container 1, formed from a light gauge of sheet metal, and provided with intake and discharge ports 2 and 3, respectively, at 45 the opposite ends thereof. The intake end of the container 1 is suitably closed by a cover 4 slidably mounted in the container 1. The interior of the container 1 is provided with a partition 5, extending longitudinally 50 therethrough to provide a plurality of chambers 6 and 7. The chamber 6 forms a match magazine, for storing a plurality of matches side by side, between the intake 2 and discharge 3. A follower member 8 is slidably 55 arranged in the chamber 7, and is provided with lugs 9 thereon which project through

slots in the partition 5 to engage the side of the match nearest the intake 2. The follower 8 is connected by springs 10, to the opposite end of the interior of the chamber 60 7, whereby said spring will be expanded when the magazine is full of matches, and in contracting the spring will move the follower 8 in the magazine, and advance the matches toward the discharge end thereof. 65 A gate 11 extends across the discharge end of the magazine and is pivoted at 12 to a projecting flange 13, formed integrally adjacent the discharge end of the magazine 6. The gate 11 is provided with a cam 14 70 thereon the underside of which is adapted to engage one end of a rocker arm 15, pivoted at 16 to the under side of the magazine 6. The opposite end of the rocker arm 15 75 is provided with a latch member 17, pivotally mounted thereon. The latch member 17 is adapted to project through a slot in the partition 5 to permit said latch 17 to enter the magazine 6, between the match nearest the discharge end thereof and the next 80 adjacent match. The gate 11 functions to hold the matches within the magazine, and when depressed or otherwise moved away from the discharge end of the magazine 85 causes the latch 17 to be moved upwardly in the rear of the match nearest the discharge to prevent a discharge of more than one match at a time from the magazine. A leaf spring 18, has one end thereof secured to the container 1, and the other end in contact 90 with the rocker arm 15, to create a tension thereon to keep the gate 11 across the discharge end of the magazine 6, except when overcome by a greater force.

95 A plate 19 is swivelly mounted on the upper face of the flange 13 on a pin 20 projecting through said flange. The plate 19 is adapted to be partially rotatable about the flange 13, and a spring 21 is coiled around the pin 20 and secured at its opposite ends 100 to the pin 20 and flange 13 for imparting a swinging motion to said plate 19. An arm 22 is pivoted at 23 to the plate 19, and the free end of the arm 22 projects part-way over the magazine 6 so as to be positionable 105 in registry with the discharge end of the magazine 6. A spring 24 is wound around the arm pivot 23 and has the projecting ends thereof extended between the said plate and arm for the purpose of elevating the arm 22 away from the upper surface of the flange 110 13. The arm 22 has a button 25 on the upper

face thereof, to facilitate easy manipulation of said arm when moving the arm into position to withdraw a match from the magazine 6. The underside of the free end of the arm 22 is provided with a depression or cavity 25' therein, which is adapted to fit around and engage the body of a match to be withdrawn from the magazine 6.

In order to withdraw a match from the magazine 6, the operator would manually depress the arm 22 from the elevated position shown in Fig. 3, to the position indicated in Fig. 2. In the depressed position the cavity 25', on the arm 22, would fit around and engage the body of the match nearest the discharge end of the magazine 6. Simultaneously with the said arm engaging the match, a projection 26 on said arm 22 would engage the cam 14 on the gate 11, and move said gate from across the discharge end of the magazine 6. The lowering movement of the arm 22 would through the interconnected mechanism cause an upward movement of the latch 17 in the rear 25 of the match to be withdrawn from the magazine. The operator would then impart an arcuate movement to the arm 22, to cause the match held by said arm 22 to be withdrawn from the magazine 6 and moved to the end of the container 1. As the arm 22 moves the match out of the magazine 6 and away from contact with the gate, said gate rises to its position across the discharge end of the magazine, (and the latch 17 lowers) 30 and the matches are automatically advanced by the spring tensioned follower 8 in said magazine.

In swinging the arm 22 and match outwardly from the magazine 6, a prescribed orbit of movement is followed in each operation. The end of the match held by the arm 22 moves on the same arc in each operation, which movement I have taken advantage of by arranging a match igniter 27, adjacent the extreme end of the magazine 6 so that the head of the match will rub over said igniter 27, and automatically light itself by the time the arm reaches the end of its movement. A pin 28 projects through the flange 18, and is adapted to limit the outward swing of the arm 22. After the operator is finished with the lighted match that has been withdrawn from the magazine in the manner described, the finger pressure on the arm 22 would be released, and the spring 24 would immediately cause the arm 22 to be elevated and to release the match and allow it to drop. In unison with the upward movement of the arm 22, a rotative movement would be imparted to the plate 19 and arm 22, by the spring 21, to swing the arm 22 back to its normal position, in registry with the discharge end of the magazine 6, in readiness for further operation.

Having thus described this invention,

what I claim and desire to secure by Letters Patent is:—

1. In combination, a match magazine having intake and discharge ports at the opposite ends thereof; means in said magazine to advance said matches from the intake to the discharge port; a spring tensioned gate pivoted to said magazine across said discharge port; and a manually operable arm on said magazine to displace said gate from said discharge port to withdraw a match from said magazine. 70

2. In combination, a match magazine having intake and discharge ports at the opposite ends thereof; means in said magazine to advance said matches from the intake to the discharge port; a spring tensioned gate pivoted to said magazine across said discharge port; a manually operable arm on said magazine to displace said gate from said discharge port to withdraw a match from said magazine; and means on said magazine to automatically ignite a match during withdrawal from said magazine. 80

3. In combination, a match magazine having intake and discharge ports at the opposite ends thereof; means in said magazine to advance said matches from the intake to the discharge port; a spring tensioned gate pivoted to said magazine across said discharge port; a manually operable arm pivotally mounted on said magazine to depress said gate and withdraw a match from said magazine; and spring means to release said match and return said arm to the discharge 90 part of said magazine. 95

4. In combination, a match magazine having intake and discharge ports at the opposite ends thereof; means in said magazine to advance said matches from the intake to the discharge port; a spring tensioned gate pivoted to said magazine across said discharge port; a manually operable arm pivotally mounted on said magazine to depress said gate and withdraw a match from said 105 magazine; means on said magazine to automatically ignite a match during withdrawal from said magazine; and spring means to release said match and return said arm to the discharge port of said magazine. 110

5. In combination, a match magazine having intake and discharge ports at the opposite ends thereof; a spring tensioned gate pivotally mounted across the discharge end of said magazine; manually operable means to depress said gate to withdraw a match from said magazine discharge port and to automatically advance the matches in said magazine toward said discharge port; and spring means to return said manually operable means to said discharge port, after the withdrawn match is released. 120

6. In combination, a match magazine having intake and discharge ports at the opposite ends thereof; a spring tensioned gate 125

pivottally mounted across the discharge end of said magazine; manually operable means to depress said gate to withdraw a match from said magazine discharge port and to 5 automatically advance the matches in said magazine toward said discharge port; means on said magazine to automatically ignite a match during withdrawal from said magazine; and spring means to return said manually operable means to said discharge port, 10 after the withdrawn match is released.

7. In combination, a match magazine having intake and discharge ports at the opposite ends thereof; a spring tensioned gate 15 pivotally arranged across the discharge end of said magazine; a manually operable arm pivotally mounted on said magazine to depress said gate to withdraw a match from said magazine; and means operated by said 20 gate to permit one match at a time to be withdrawn from said magazine.

8. In combination, a match magazine having intake and discharge ports at the opposite ends thereof; a spring tensioned gate 25 pivotally arranged across the discharge end of said magazine; a manually operable arm pivotally mounted on said magazine to de-

press said gate to withdraw a match from said magazine; means operated by said gate to permit one match at a time to be withdrawn from said magazine; and an abrasive 30 on said magazine to automatically ignite a match during withdrawal from said magazine.

9. In combination, a match magazine having intake and discharge ports at the opposite ends thereof; a spring tensioned gate 35 pivotally arranged across the discharge end of said magazine; a manually operable arm pivotally mounted on said magazine to de- 40 press said gate to withdraw a match from said magazine; means operated by said gate to permit one match at a time to be withdrawn from said magazine; an abrasive on said magazine to automatically ignite a 45 match during withdrawal from said magazine; and spring means to automatically return said arm to the discharge end of said magazine.

In testimony whereof, I have hereunto set 50 my hand at San Francisco, California, this 19th day of March 1924.

JULIUS CASACCIA.
